UNITED STATES PATENT OFFICE.

OTTO SAGER, OF ROCHESTER, NEW YORK.

CONCRETE-WALL MOLD.

1,206,598.

Specification of Letters Patent. Patented Nov. 28, 1916.

Application filed April 14, 1916. Serial No. 91,179.

To all whom it may concern:

Be it known that I, OTTO SAGER, a citizen of the United States, residing at Rochester, in the county of Monroe and State of New York, have invented new and useful Improvements in Concrete-Wall Molds, of which the following is a specification.

This invention relates to an improvement in molds for use in molding concrete walls of buildings and other structures.

One object of my invention is to provide a mold of this character which forms a wall having spaced ribs on its inner side and thereby forms air channels between the ribs.

Another object is to provide the inner and outer mold sections with reinforcing bars of improved construction.

Another object is to provide improved means for detachably securing the inner and outer mold sections together.

Another object is to provide improved means for detachably securing the mold sections together.

Another object is to provide means for molding a joist-supporting sill which extends across the air chambers.

Another object is to combine furring strips with the inner mold sections to cause said furring strips to be molded in the wall and used for securing the lathes.

The invention consists in the features of construction, combination, and arrangement of devices, hereinafter fully described and claimed.

In the accompanying drawings:—Figure 1 is a perspective view of a concrete wall mold constructed and arranged in accordance with my invention and showing the same in use in molding walls which are united and are arranged at right angles to each other. Fig. 2 is a vertical sectional view of the same. Fig. 3 is a horizontal sectional view of the same. Fig. 4 is an elevation showing the inner side of the outer mold section and the strips thereon which divide the outer surface of the molded wall into panels and give the same the appearance of being constructed of concrete blocks. Fig. 5 is a detail perspective view of the sill forming mold member. Fig. 6 is a detail sectional view on a larger scale, and in a horizontal plane. Fig. 7 is a detail perspective view showing mold members ar-

ranged angularly to each other as when forming an angle between walls or a structure corner.

My improved concrete wall mold comprises outer sections 1 and inner sections 2. These sections are made of plate metal and each section is reinforced on its outer surface by means of horizontally arranged channel bars 2 which may be made of iron or any other suitable material. The sections are preferably square and any suitable number of the sections may be provided, according to the length of the wall or walls to be molded, and said sections are detachably secured together by strips 4 of iron or steel which are arranged in the channels of the channel bars, extend across the joints between the sections and are arranged in overlapping relation from said joints, one end of each strip being offset as at 5 to abut against the meeting end of the companion strip and to provide an overlapping arm 6 which bears against the outer side of said companion strip. The channel bars are permanently secured to the mold sections by means of rivets or the like and serve to reinforce the mold sections and to also hold them straight and keep their surfaces plane.

Bolts 7 pass through the wall A, formed between the inner and outer mold sections and also pass through the channel bars and the strips 3 and are provided on their threaded ends with nuts 8 each of which is arranged in a tubular shield 9, the said shields may be grasped by means of a suitable wrench and turned to turn the nut on the bolt for tightening or loosening the mold sections and said shields serve to protect the projecting threaded ends of the bolts from injury and prevent dirt or particles of concrete from coming in contact with the threaded portions of the bolt.

The inner and outer mold sections are held in proper spaced relation, according to the thickness of the wall by tubular spacer members 10, 11 of unequal length, the shorter tubular spacer members 10 being rigidly secured to the outer wall members and hence removable therewith from the wall after the latter is molded, and the longer inner tubular spacer members 11 being not attached to the inner mold sections and being left permanently in the molded

wall, when the mold sections are removed therefrom. Hence horizontal openings are formed in the wall when the latter is molded and the inner portion of each of said openings is lined by one of the inner tubular spacer members 11. When one course of the wall has been molded and the mold is raised to be used for molding another course, the mold sections will be supported in the required elevated position by their lowermost bolts 7 which will pass through the uppermost series of tubular members 11 embodied in the finished lower course, as will be understood. Hence the said tubular members 11 not only serve in connection with the tubular members 10 to space the inner and outer mold sections, but also serve in connection with the bolts to support the mold sections in raised position, from course to course as the molding of the wall proceeds.

The inner mold sections 2 are provided on their inner sides with vertically arranged core formers 13, which are appropriately spaced apart and which serve to form the wall with vertical ribs B on its inner side and which are spaced apart and hence form air chambers C between the ribs. When it is desired to form a solid wall, such as shown at D in Fig. 1, the core formers are omitted.

Where the core formers are used, I also employ furring strips 14 which are arranged on the inner wall sections between the core formers and which are cast in the wall as the latter is molded so that the said ribs of the wall are provided with furring strips on which the lath may be nailed.

To enable the wall to be formed with an outer surface, divided into panels to simulate a wall constructed of blocks, I provide strips 14 which are suitably spaced apart and arranged in crossed and in broken joint relation. The said strips are here shown as triangular in cross section, but may be of any other suitable shape.

In the angle between the walls, or in a corner of the structure, the inner mold member includes angle sections 15, each of which is provided on its inner side with angled channel bars 16, to aline with channel bars 17 and is also provided with angled strips 17 to aline and coat with the strips 4. Mold members 18 are also arranged at right angles to the outer wall member 1 and in suitably spaced relation to the members 15, and are provided on their outer sides with channel bars 19 and strips 20. Said channel bars have closed outer ends 21, and said members 18 are secured to the members 1 by bolts 22, which pass through and engage with said outer ends of said channel bars.

Rods 23 pass through horizontal openings in the core formers 13 and after the wall is molded are then withdrawn and hence serve to form openings which extend through the ribs B.

To enable a sill E to be molded at the required height to support joists, I provide a mold member 24 which is a metal plate of suitable length and width and which is provided on the inner side with horizontal, in-turned portions 25 which are suitably spaced to correspond with the air chambers of the wall A and extend across the upper ends of said air chambers, and form bottom portions to support the sill E, the lower portions of the wall 26 of said mold member extending downwardly and bearing against the inner side of the upper portion of the inner mold section or sections 2. This mold member may be removed after the sill portion of the wall has been molded and the vertical extension of the molding continued by the inner and outer mold members, as hereinbefore described.

Having described the invention, what is claimed is:

1. In a mold of the class described, sections, channel bars arranged on the outer sides of the sections, and strips detachably secured in the channel bars and extending across the joints between and connecting the sections together.

2. In a mold of the class described, sections, reinforcing angle bars arranged on the outer sides of the sections, and strips detachably secured to said reinforcing bars and extending across the joints and connecting the sections together.

3. In a mold of the class described, inner and outer sections having reinforcing bars on their outer sides, strips arranged on the reinforcing bars and extending across the joints between the sections, and spacing and connecting means between the inner and outer sections, said spacing and connecting means also detachably securing the strips in place.

4. In a mold of the class described, inner and outer sections having channel bars on their outer sides, strips arranged in the channels of the channel bars and extending across the joints between the sections, and bolts connecting the inner and outer sections together, and also detachably securing the strips in place.

5. In a mold of the class described, inner and outer sections, bolts connecting the inner and outer sections together, tubular spacer elements on the bolts, permanently secured to the outer sections, and tubular spacer elements on the bolts and arranged between the first-named spacer elements and the inner sections, the last-named tubular spacing means being detachable from the bolts and hence left in the wall molded between said inner and outer sections.

6. In a mold of the class described, sections, reinforcing bars detachably secured on the outer sides of the sections, and strips detachably secured on said reinforcing bars

and extending across the joints between the sections and arranged in overlapping relation.

7. In a mold of the class described, inner and outer sections, a hollow core member open at its upper end and arranged between said sections, and a transversely angular mold member for arrangement on the upper sides of said sections and core member and

having a portion extending across and closing the top of the core member and also having an upwardly extending wall to permit a joist supporting sill to be molded above the air chamber formed in the molded wall by the core element. 10
15

In testimony whereof I affix my signature.

OTTO SAGER.
